UNITED STATES PATENT OFFICE.

CHARLES MCKEEVER, OF JERSEY CITY, NEW JERSEY, ASSIGNOR OF ONE-THIRD TO WILLIAM H. DICKINSON AND ONE-THIRD TO CLEM B. MEARS, BOTH OF NEW YORK, N. Y.

VEHICLE-LAMP.

1,233,082.

Specification of Letters Patent. Patented July 10, 1917.

Application filed October 4, 1916. Serial No. 123,616.

To all whom it may concern:

Be it known that I, CHARLES MCKEEVER, a citizen of the United States, residing at Jersey City, county of Hudson, and State 5 of New Jersey, have invented an Improvement in Vehicle-Lamps, of which the following is a specification.

My present invention relates to a lamp and particularly to a lamp adapted for use 10 in a motor vehicle. So far as I am aware the lamps commonly employed on motor vehicles including automobiles, trolley cars and the like, are made with a reflector adapted to receive a socket and an electric 15 lamp bulb. In this form of lamp irrespective of the position the bulb may assume, the filaments of the bulb are visible and the light reflected by the reflector often times causes such a glare as to make it impossible 20 for drivers of other vehicles to see anything but the bright light in the road. The object of my present invention is to overcome this difficulty, and to provide a vehicle lamp which will come within the requirements of 25 the law in many places as to the amount and direction of the lights carried by motor vehicles.

In carrying out my invention together with an electric lamp bulb and a socket, 30 therefore, I employ a transparent cup member adapted to fit over the lamp bulb as well as around a portion of the socket, and a cap member preferably comprising a rim adapted to be secured to the edge of the cup 35 and a disk provided with an aperture to receive the point of the lamp bulb so that the cup is supported and maintained in position upon the lamp socket and by the said cap, the disk of which makes it impossible to 40 view directly the filament of the lamp bulb while the cup member is so constructed as to diffuse and direct the light to the amount and in the direction required by the law in many places.

45 In the drawing Figure 1 is a central cross section of a vehicle lamp made in accordance with my invention. Fig. 2 is a plan view of the cup and cap in position relatively to the lamp bulb.

50 Referring to the drawing, 10 indicates a reflector which may be suitably secured in any form of casing commonly employed in lamps for motor vehicles. At the base of the reflector the same is provided with a lamp socket 11 which may be fixed in posi-

tion as shown in Fig. 1 or made adjustable to position within predetermined limits to regulate the focus of the light. As is customary an electrical lamp bulb 12 is employed. This lamp bulb is provided with a 60 base 13 having oppositely disposed pins 14 adapted to enter the slots 15 in the lamp socket 11 to secure the lamp bulb in place and make the necessary electrical connections for lighting the lamp. 65

Together with these features which heretofore have been commonly employed in vehicle lamps, I employ a cup member 16 made of suitable glass or other sufficiently transparent material. The base of the cup member 16 is provided with an opening 17, adapted to receive the end of the lamp socket 11. The periphery of the cup member 16 adjacent the edge thereof is preferably ribbed as indicated at 18, while that portion 19 of the cup adjacent the base is plain. The object of this as disclosed in my co-pending application, Serial No. 107,078, filed July 1, 1916, is to diffuse the rays of light from the lamp, and to direct them immediately in front of the lamp within a predetermined scope depending upon the area of the plain surface at the base of the cup member, it being apparent that the rays of light passing through the ribbed portion of the cup member will be generally diffused by the reflector, while the rays of light passing through the base of the cup member will be reflected through the same again immediately in front of the lamp. 90

In my present invention I also employ a cap member 20, preferably made of metal, although it may be constructed of other suitable material. This cap member comprises a rim 21, adapted to fit and be connected to the edge of the cup member as well as a disk 22, provided with a central opening 23, to receive the point 24 of the lamp bulb. The disk 22 is connected to the rim 21 by means of suitably spaced arms 25 or otherwise, and the diameter of the disk is such as to prevent the direct vision of the filament of the lamp bulb when lighted. The rim 21 is provided with lugs 26, adapted to engage threads 27, provided for this purpose on the exterior of the cup member adjacent the edge thereof in order to secure the cap in position, it being apparent as hereinbefore stated that the cup member is supported and maintained in position by 105 110

the lamp socket, the cap and the bulb. It will also be understood that when the socket is made adjustable to position it may be moved toward the reflector until the cup 5 contacts with the reflector and this also assists in maintaining the cup in place.

I claim as my invention:

1. In a vehicle lamp and in combination with a lamp bulb and a socket therefor, a 10 transparent cup fitting over said lamp bulb, and having an opening in the base thereof to receive the said socket, and a device secured to the edge of the cup to prevent the direct vision of the filament in the lamp 15 bulb, and to co-act with the lamp socket and bulb in maintaining the cup in position.
2. In a vehicle lamp and in combination with a lamp bulb and a socket therefor, a glass cup fitting over said lamp bulb and having 20 an opening in the base thereof to receive a portion of the said lamp socket, and a cap secured to the edge of the said cup to prevent the direct vision of the filament in the lamp bulb, and to co-act with the lamp 25 socket and bulb in maintaining the cup in position.
3. In a vehicle lamp and in combination with a lamp bulb and a socket therefor, a glass cup fitting over said lamp bulb and 30 having an opening in the base thereof to receive a portion of the said lamp socket, a rim secured to the said glass cup, and a disk

connected to the said rim and adapted to prevent the direct vision of the lamp bulb filament, and also to co-act with the said 35 lamp socket and bulb to maintain the glass cup in position.

4. In a vehicle lamp and in combination with a reflector, an electric lamp bulb and a socket therefor, a glass cup fitting over 40 said electric lamp bulb, and having an opening in the base thereof adapted to receive a portion of the lamp socket, a disk having an aperture therein to receive the point of the electric lamp bulb, a rim adapted to be secured to the edge of the glass cup, and means connecting the said disk and rim.

5. In a vehicle lamp and in combination with a reflector, an electric lamp bulb and 50 a socket therefor, a glass cup fitting over said electric lamp bulb, and having an opening in the base thereof to receive a portion of the said lamp socket, a disk having a central aperture to receive the point of the 55 electric lamp bulb, a rim, means connecting the disk and rim, and lugs on the inner side of the said rim adapted to engage the edge of the glass cup to secure the said rim and disk in position thereon.

Signed by me this 21st day of September, 1916.

CHARLES McKEEVER.
